UNITED STATES PATENT OFFICE.

LESTER S. RILEY, OF BOSTON, MASSACHUSETTS, ASSIGNOR OF ONE-HALF TO ATWOOD L. BOGGS, OF BOSTON, MASSACHUSETTS.

BILL OR LETTER FILE.

1,130,631.

Specification of Letters Patent.

Patented Mar. 2, 1915.

Application filed August 29, 1913, Serial No. 787,341. Renewed July 20, 1914. Serial No. 852,089.

To all whom it may concern:

Be it known that I, LESTER S. RILEY, a citizen of the United States, residing at Boston, Massachusetts, have invented certain new and useful Improvements in Bill or Letter Files, of which the following is a specification.

This invention is designed to provide a very simple but effective device for taking care of bills or letters, being an improvement over the ordinary bill file which usually consists of a base and upwardly projecting spindle having a tapering point upon which the bills or other sheets are impaled. In the ordinary file the papers are easily displaced, or if protected from displacement it is difficult to keep them in proper order as they are removed from the file, and my invention is designed to prevent displacement of the papers on the file and at the same time readily provide their removal in the order in which they have been placed in the file, and to permit of their storage without changing the order in which they were placed upon the file.

In the drawing, Figure 1 is a side elevation of the device in position to receive the bill, letter or other paper. Fig. 2 shows the device with the parts in the position to prevent displacement of the papers, and Fig. 3 shows a section.

I may utilize an ordinary base A of sufficient weight to keep the spindle B upright, and over this spindle I place a sheath C, this being split at its lower end as shown at D to give a spring effect and make a comparative tight fit. The sheath is bifurcated at its upper end, shown at b and pivoted within this bifurcation is an impaling point d preferably of the shape shown, narrow at the center where the pivot passes so as to be about equal with the diameter of the sheath with protruding portions on each side of the center as at e, terminating in points f. The impaling plate d is freely pivoted and may assume a vertical or horizontal position, as shown. In its vertical position the papers may be impaled and pass over it to the sheath, and when it is desired to retain the

papers in place and prevent their detachment from the sheath the part d is simply changed to a horizontal position. Slight projections g are made in the metal of the plate d on each side of its pivot so as to require pressure to change the plate from a horizontal to a vertical position. The top of the sheath is rounded as shown at h, and in practice I have found that the construction shown permits the filing of papers on the spindle without ripping the paper or making a ragged hole. I make perforations i at the lower end of the sheath in which I insert a string, and when it is desired to remove the accumulation from the file the sheath may be drawn through the letters or bills carrying with it the string, so as to thread the bills upon the string and the ends of the string may then be tied to secure the papers safely in the relation in which they were filed, the papers being withdrawn from the spindle and filed away.

What I claim is:—

1. A safety bill or letter file comprising a base, a spindle, a removable sheath having a pivoted impaling point carried at its upper end and adapted to assume a vertical or horizontal position as required, substantially as described.

2. In combination in a base, a spindle, a sheath, an impaling point pivoted thereto having double ends of uniform shape and adapted to assume either a vertical or a horizontal position, substantially as described.

3. In combination with a base, a spindle, a sheath having an impaling point with means for locking the impaling point in a vertical position, substantially as described.

4. In combination with a base, a spindle, a sheath removable from said spindle having an impaling point and a threading eye at the lower end of the said sheath, substantially as and for the purpose set forth.

In testimony whereof, I affix my signature in presence of two witnesses.

LESTER S. RILEY.
